UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

RAILWAY CAR.

Application filed March 16, 1925. Serial No. 15,748.

This invention relates to improvements in railway cars.

An object of the invention is to provide a dumping door construction for railway cars of the general service type, in which the parts of each door are of metal, and arranged and braced in a novel manner, including elongated embossments in the unsupported portion of the door to reinforce the body thereof where the same is likely to sag under load, and including means for strengthening the free edge and corner portions of the door to render the construction of exceptional value when associated with operating mechanism wherein the door is supported upon a bodily movable shaft.

Another object of my invention is to provide operating mechanism for controlling the movements of the dumping doors, such mechanism including the so-called creeping shaft, which is mounted upon the car structure and adapted for bodily movement to and from positions beneath the doors when the same are closed, in conjunction with novel actuating means mounted on the car structure, and operative to rotate the shaft to move the same into, and out of, positions beneath the doors, and wind and unwind connecting elements between the shaft and doors.

Still another object of the invention is to provide a novel form of locking mechanism for preventing retrogressive rotation of the operating shaft, the construction being such that the locking means is operable at all times irrespective of wear between the parts due to the fact that the locking element travels with the shaft, and is normally urged to operative engagement by gravity.

Other and further objects of the invention will more fully and clearly appear from the description and claims hereinafter following.

In the drawings forming part of this specification, Figure 1 represents a fragment of one side of a railway car, of the general service type, showing a top plan view of means providing a dumping opening in the bottom of the car, and a hinged dumping door associated therewith. Figure 2 is a transverse sectional view of the car structure, substantially on the line 2-2 of Figure 1. Figure 3 is a side elevational, partially sectional view, of the dump door and

operating shaft, the side wall of the car being omitted to afford an unobstructed view of the mechanism. Figure 4 is an end elevation of a fragment of the car, showing an end view of the shaft operating mechanism in its normal inoperative position, with the shaft disposed beneath the doors to retain the same in closed position. Figure 5 is a view similar to Figure 4, the actuating member being omitted to more clearly expose the locking mechanism used in connection with the invention, the locking mechanism in this figure being shown in locking position. Figure 6 is a view similar to Figure 5 showing the locking member held in an unlocked position. Figure 7 is an enlarged side elevation of the shaft actuating device, the locking mechanism, and the structure upon the end wall of the car upon which the mechanism is mounted. Figure 8 is a view similar to Figure 4 showing the actuating device when in final closing position in which the shaft is disposed beneath the doors to support the same in closed position. Figure 9 shows a view similar to Figure 8, in which the actuating device is illustrated in position to start the movement of the shaft from its position beneath the doors so as to open the doors and Figure 10 shows the actuating device in position to begin the winding of the shaft to close the doors.

As shown in the drawings 10 represents a fragment of the center sill of a railway car of the general service type; 11 represents a fragment of the side sill of such car, only one side of the car being illustrated, and it will be understood that the center and side sills 10 and 11 extend longitudinally throughout the length of the car, and that a construction similar to that illustrated in Figure 1 forms the opposite side portion of the car. The center and side sills 10 and 11 are connected at intervals by means of cross bearers 12 which are connected to the side and center sills in any suitable manner. Mounted along the top surfaces of the cross bearers are transversely disposed floor portions 13 and 14, and upon the center and side sills are longitudinally extending floor portions 15 and 16, the floor portion 16 preferably being in the form of an angular member as shown, the various parts of the car on both sides being arranged in a similar manner, and as shown defining dumping

openings 17. The cross bearers 12 are provided with elongated slots 18, at their outer ends, each slot being reinforced by means of brackets 19, secured to the cross bearer, the brackets having slots similar to the slot 18, the members being formed to provide a depression 20 at the outer end of each slot. Mounted for rotation in the slots 18 is the winding shaft 21, such shaft being capable 10 of free rotation, and bodily translation, within the slots 18 in the cross bearers. Each shaft 21 preferably extends throughout half the length of the car through the various cross bearers 12, and is provided at intervals 15 with gears 22, preferably two to a door opening, and disposed in position to engage co-operative means on doors associated with the openings which will be hereinafter more fully described. Each of such gears has 20 formed therewith a drum 22', to which is adapted to be connected a chain or the like as hereinafter referred to.

My improvements broadly, reside in the doors A for closing the dumping openings, 25 the locking mechanism B for the operating shaft and an actuating device C for imparting rotation to the operating shaft.

As above referred to a plurality of doors A are provided, one for each of the dumping openings 17 in the bottom of the car. 30 Each of the doors A is of a novel construction comprising a metal plate of a size slightly greater than the dumping opening with which it is associated, such plate being 35 provided along its forward and side edges with depending integral flanges 23, 24 and 25, and with a rear flange 26 which is inclined rearwardly and curved, so as to fit beneath the floor portion 15 associated with 40 the center sill.

Each of the doors A is swingably mounted upon the center sill 10 by means of hinge butts, preferably three in number which are secured to the center sill by means of rivets, 45 and in spaced relation, two of the hinge butts 27 preferably being located adjacent the side edges of the door opening, and the remaining hinge butt 28 mounted centrally between the two outer hinge butts. The 50 hinge butts 27 and 28 are cut out to accommodate the curved flange 26 upon the door plate. The central hinge butt 28 is connected to the plate forming the door A by means of a hinge strap 29 riveted to such 55 door and pivotally connected with the hinge butt by means of the pivot pin 30. The two outer hinge butts 27 are also provided with hinge straps 31 pivotally connected with the associated hinge butts 27 by means 60 of pivot pins 32. Door braces 33 are provided which are in the form of angle members, one flange of which is secured to the door plate by means of rivets, and the other flange of which is disposed inwardly of the 65 side edge of the door, and lies substantially

perpendicular to the plane of the door plate. The door braces 33 extend transversely across the door plate to a point adjacent the outer free edge thereof, the rear ends of the door braces being disposed in position to be 70 secured to the hinge straps 31, rivets being provided which extend through the hinge straps 31, the horizontal flanges of the braces, and the door plate.

Adjacent the forward edge of the door, 75 and terminating a slight distance from the door braces 33 is a longitudinally extending brace in the form of a Z bar 34 one horizontal flange 35 of which is riveted to the door plate, the other horizontal flange 36 being 80 disposed somewhat below the plane of the door plate and the web of the Z bar being disposed perpendicularly to the plane of the door plate.

Interposed between each end of the Z bar 85 34, and the adjacent vertical flange of a door brace 33 is an angular member 37, one flange of which lies between the end of the Z bar and the adjacent vertical flange of the brace, and the other flange of which is secured to the flange 36 of the Z bar 34 by means of rivets. Disposed on the outer side of each vertical flange of the related door brace 33 is a rack casting 38, provided with a rack 39 on its under surface, which rack cooperates with the wheel 22 to keep the door shut, the flange 23 of the door plate being recessed as indicated at 40 to permit the projection therethrough of the outer end of the rack on the casting. The side wall 41 of the casting lying against the vertical flange of the adjacent brace 33 is fastened in position by means of rivets 32 which extend through the wall 41, the vertical flange of the adjacent door brace, and the vertically disposed flange of the supporting plate 37. The top wall 42 of the casting is secured to the door plate by means of rivets 43. Each casting 38 is reinforced by suitable ribs 44, and a depending flange 45. The casting is also provided with an eye 46 for the reception of a chain or other suitable connection member (not shown) between the door and the operating shaft.

In order to strengthen the portion of the 115 door plate lying between the braces 33, the metal is pressed upwardly to provide embossments 48, which are of elongated oval or elliptical form, the major axes of which extend perpendicular to the pivotal axis of 120 the door, the extremities of the embossments at their outer ends extending approximately to a point in line with the web of the Z-bar 34, and their rear ends extending to a point adjacent the rear edge of the door. The minor axes of such embossment are of such extent as to provide approximately equal spaces between the outer sides of the embossments and the braces 33, and between 125 the inner adjacent faces of the embossments, 130

the embossments covering approximately two thirds of the area of the door between the braces 33. Each of the embossments 48 has a flat upper surface of extended area which is joined to the main body of the plate by inclined wall portions 48', the inclined wall portions extending at such an angle that in shoveling the load, should it be desired to do so, the shovel will slide easily over the sloping surfaces of the embossments, and also that the greatest length is at the forward and rear ends of the embossments to provide for an unobstructed flow of material when the doors are opened. The construction of the door can be somewhat varied if desired so that the center hinge strap 29 may be extended toward the Z-bar 34 a sufficient distance to provide a stiffener in which event the embossments 48 could be made smaller in size. By this arrangement it will be apparent that the door is braced by the members 33, and by the Z-bar, and the rack members are securely connected by the plates 37 both to the braces 33 and the Z-bar so that the rack members which support the door upon the shaft are supported by the framework, and not by the metal of the plate itself. It also should be noted that the embossments brace the portion of the door which is most likely to sag under the weight of the load imposed thereon, such embossments being arranged so that the portion of the door between the underlying reinforcements is braced in a simple and economical manner. The detailed construction of the door as above described is not claimed herein, but forms subject matter of a divisional application.

Means, including the locking mechanism B, and actuating device C, are provided for operating the shaft 21 for opening and closing the doors A, one end of the shaft 21 terminating a slight distance beyond the end wall of the car. The end wall construction of the car is modified in order to afford means for applying actuating and locking mechanism for operating the shaft 21 to open and close the doors. This end wall construction includes the usual end sill 50, through which the shaft 21 passes, the end of the shaft projecting beyond the end sill as indicated at 51. The wall 52 of the car is provided with an outwardly turned flange portion 53 as shown. Secured to the outer face of the end sill 50 is a bracket 54, such bracket being provided with an upper flange 55 which is secured to the flange member 53 by means of rivets 56. The bracket is also provided with an offset portion including a transversely disposed wall 57, which is provided with a centrally disposed slot 58, the remaining angular portion 59 of the bracket extending parallel with the body portion of the bracket. Bracing plates 60 and 61 are secured to the end sill, and to the bottom of

the bracket so that the same is securely held in position.

Fixedly attached to the projecting end portion 51 of the shaft 21 at some little distance from the end thereof is a ratchet wheel 61, such ratchet wheel being provided with hubs 62 on its opposite sides. Loosely mounted upon the hubs of the ratchet wheel 61 are plates 63, the inner end portions of such plates being reduced as indicated at 64, such reduced portions extending through the slot 58 in the transverse wall 57 of the bracket, the reduced portions being secured together by suitable spacers and rivets 65. The outer ends of the plates 63 are disposed outwardly of said shaft and below the same, providing extensions 66, the outer extremities of such extensions being secured together by a pivot pin 67 upon which is pivotally mounted a locking cam 68, which is provided with an offset 69 at one end. The inner portions 70 of the extensions 66 are also secured together by means of a pivot pin 71 upon which is pivotally mounted a gravity operated locking pawl 72. Such pawl is provided with a finger 73 adapted to engage the ratchet wheel 61, and the finger 73 is held in engagement by the weighted tail portion 74 of the pawl 72. The pawl 72 is provided with a finger 73 adapted to engage the ratchet wheel 61, and the finger 73 is held in engagement by the weighted tail portion 74 of the pawl 72. The tail portion of the pawl 72 is provided with a notch 75 adapted in certain positions to be engaged by the offset member 69 of the cam 68, as shown in Figure 6. It will also be noted that the cam 68 may be turned to position to lock the pawl 72 in engagement with the ratchet wheel 61, as shown in Figure 5.

The actuating mechanism C is carried by the bracket and the end wall of the car. This mechanism includes a supporting element 76 having arms 77 at each side thereof which extend inwardly beneath the flange 55 of the bracket, such arms being secured to the bracket and to the flange 53 of the end wall by means of the rivets 56, and to the bracket by means of rivets 79. The supporting element 76 is disposed some distance outwardly from the locking mechanism B, and is provided centrally with journal bearings 80 and with a recess 81, the recess 81 being for the reception of the journal portion 82 of the actuating lever 83, which is adapted to be pivotally mounted on the supporting element 76. The supporting element 76 is provided with a curved flange 76' for limiting the swinging movement of the lever 83. The portion of the actuating lever disposed in the cavity 81 of the supporting element 76 is provided with a bore, and a pivot pin 84 is provided which extends through the journal bearings in the supporting element and through the bore in the related

portions of the lever 83 and secured by some means as a pin. The body portion of the lever 83 is offset relative to the portion 82 carried by the pivot pin 84, and such body portion is provided with suitable openings 85 for the reception of a claw bar in the usual manner. The lower depending portion 86 of the lever 83 carries a pivot pin 87 upon which is mounted an operating pawl 88, which is adapted in certain positions to effect rotation of the shaft 21 by engagement with a toothed member 89 which is keyed to the outer extremity 90 of the shaft 21. The pawl 88 is provided with an engaging portion 91, which is located a predetermined distance from the pivot pin, and is also provided with an engaging portion 92 which is located a relatively less distance from the pivot pin 87, the pawl 88 being swingably mounted whereby the portion 91 may be engaged with the toothed member 89 when it is desired to rotate the member 89 to close the doors, and to engage the portion 92 of the pawl with the toothed member 89 when it is desired to rotate the toothed member for imparting opening rotation to the shaft 21. The teeth 93 of the ratchet wheel are somewhat undercut as indicated at 94, and the engaging portions 91 and 92 of the pawl 88 are shaped for the most efficient engagement between the parts to prevent accidental disengagement thereof.

In operation assuming the shaft 21 and the toothed member 89 associated therewith to be in a released position as indicated in Figure 10, the lever portion 83 of the actuating mechanism may be swung outwardly toward the side wall of the car, and the portion 91 of the pawl 88 engaged with a tooth 93 of the member 89. A bar may be inserted into the openings 85, and the lever member swung inwardly which will cause a counter-clockwise rotation of the member 89, and of the shaft 21. When the lever has been swung the maximum distance inwardly, the same is again swung outwardly and the portion 91 of the pawl 88 reengaged with a different tooth of the member 89, and the operation repeated until the connections between the shaft and the door are wound upon the shaft and the same begins its bodily inward movement, at which time the gears upon the shaft will engage the racks 39 upon the rack members which are secured to the doors, so that further operation of the lever will move the shaft to position beneath the door, so as to support the same in closed position. During this movement retrogressive rotation of the shaft 21 is prevented due to the engagement of the pawl 72 with the ratchet wheel 61, the pawl of course following the ratchet wheel due to the fact that the members which carry the pawl move with the shaft.

When the shaft is in fully closed position

the pawl may be locked against movement by turning the cam member 68 thereagainst, Figs. 4 and 5.

When it is desired to open the doors, the cam member 68 is turned to the position shown in Figure 6 so as to hold the pawl out of engagement with the ratchet wheel 61. The lever 83 of the actuating mechanism is then swung inwardly, and the portion 92 of the pawl 88 engaged with a tooth of the member 89 as shown in Figure 9. By inserting a suitable bar in the openings 85, the lever 83 may be swung outwardly, rotating the member 89, and the shaft 21, in a clockwise direction, causing the shaft to travel out from beneath the doors due to the engagement of the gears on the shaft and the rack members on the door, the shaft after this position is reached, freely rotating to permit the complete opening of the doors.

It should be noted in connection with the mechanism above described that the locking pawl follows the shaft and the related ratchet mechanism, and due to its mounting with the weighted end urging the same into position, the pawl automatically compensates for wear, and there is no possibility of failure in operation. It should also be observed that the actuating mechanism is mounted upon the car structure, and does not travel with the shaft, and hence there is absolutely no likelihood of the actuating member rotating with the shaft when the same tends to unwind under the weight of the load imposed thereon, and therefore is safe to operate and provides a very economical and efficient construction.

While I have herein shown and described what I now consider the preferred manner of carrying out my invention, the same is merely illustrative and I contemplate all changes and modifications that come within the scope of the claims appended hereto.

I claim:

1. In a dump car, the combination with a bodily translatable door operating shaft; of a toothed wheel on the shaft; a fulcrum disposed on the car structure above the shaft; a lever member carried by said fulcrum; and means carried by the lever adapted to engage the toothed wheel to rotate the shaft.

2. In a railway car, the combination with a bodily translatable shaft; of a ratchet wheel fixedly mounted on the shaft; a lever pivotally mounted on the car structure above the level of the shaft; and a pawl pivotally mounted on the lever at a point below the level of the shaft, said pawl being adapted to have engagement with the ratchet wheel to rotate the shaft by oscillations of the lever.

3. In a car door operating mechanism, the combination with a bodily translatable shaft; of a toothed member on the shaft; a

- fulcrum above the shaft; a lever pivotally mounted on the fulcrum, said lever having a web portion adapted to swing in a plane adjacent the toothed member; a pawl pivotally carried by the lever and disposed in the plane of the toothed member for engagement therewith; and lever receiving means formed on the web portion of the lever and disposed on the side opposite to the said pawl.
4. In a railway car, the combination with dumping doors; of a bodily translatable shaft movable to and from a position beneath said doors when rotated; a support secured to said car structure; a member pivotally mounted upon said support and normally independent of said shaft; a toothed member on said shaft; and an operating pawl movable into engagement with said toothed member, and operable upon movement of said actuating member to rotate said toothed member, said operating pawl being reversible to rotate said shaft in either direction, one operating portion of said pawl being of greater length than the other.
5. In a railway car, the combination with dumping doors; of a bodily translatable operating shaft movable to and from a position beneath said doors when rotated, said shaft projecting beyond the end sill of the car and being provided with a toothed member; a support on the car structure comprising an outturned flange on the end wall thereof; a supporting bracket mounted on said flange; an operating lever pivotally mounted on said supporting member; and an operating pawl adapted to engage said toothed member to rotate said shaft.
6. In a railway car, the combination with dumping doors; of a bodily translatable operating shaft movable to and from a position beneath said doors when rotated, said shaft projecting beyond the end sill of the car and being provided with a toothed member; a support on the car structure comprising an outturned flange on the end wall thereof; a supporting bracket mounted on
- said flange; an operating lever pivotally mounted on said supporting member; an operating pawl adapted to engage said pivotally mounted member to rotate said shaft; and means for locking said shaft against rotation.
7. In a railway car, the combination with pivoted dumping doors; of a bodily translatable shaft movable to and from a position beneath said doors when rotated, said shaft projecting beyond the end sill of the car; a bracket secured to the end sill of the car and provided with an offset portion having means forming a guide; a ratchet member mounted on said shaft and provided with hubs on its opposite side; plates rotatably mounted on the hubs of said ratchet wheel and having extensions connected together and slidably mounted in said guide, said plates being provided with portions disposed outwardly of, and below, said shaft; a locking pawl pivotally mounted between said portions and adapted to engage said ratchet wheel; a toothed member secured to the outer end of said shaft; a support on the end structure of the car comprising an outwardly turned flange; a supporting bracket secured to said flange and said bracket; a lever pivotally mounted on said supporting bracket; and an operating pawl pivotally mounted on said lever and adapted to engage said toothed member for rotating said shaft.
8. In a car door mechanism, the combination with a bodily translatable shaft; of a ratchet wheel fixedly mounted on said shaft; a lever pivotally mounted on the car structure at one side of the shaft; and a pawl pivotally mounted on the lever at a point on the other side of said shaft, said pawl being adapted to have engagement with the ratchet wheel to rotate the shaft by movement of the lever.

In witness that I claim the foregoing I have hereunto subscribed my name this 13th day of March, 1925.

ARGYLE CAMPBELL.
